UNITED STATES PATENT OFFICE.

HARLAN P. GARDNER AND GEORGE W. BEAR, OF ST. PAUL, MINNESOTA.

DESIGN FOR A PIN, BROOCH, BUTTON, EMBLEM, RING, OR ARTICLE OF A SIMILAR NATURE.

52,646.

Specification for Design.

Patented Nov. 12, 1918.

Application filed August 17, 1918. Serial No. 250,609. Term of patent 7 years.

To all whom it may concern:

Be it known that we, HARLAN P. GARDNER and GEORGE W. BEAR, citizens of the United States, residing at St. Paul, county of Ramsey, and State of Minnesota, have invented a new, original, and ornamental Design for a Pin, Brooch, Button, Emblem, Ring, or Articles of a Similar Nature, of which the following is a specification, reference being had to the accompanying drawings, forming part thereof.

The figure is a plan view of our ornamental design used on a pin, brooch, but-

ton, ring or articles of a similar nature, and which illustrates a shrieking eagle with partly spread wings positioned on a shield having a red border, an inner field of blue which is circumscribed by a white margin, separating the red border from the blue field, and a white star in the blue field.

We claim:

The ornamental design for a pin, brooch, button, emblem, ring, or article of a similar nature, as shown.

HARLAN P. GARDNER.
GEORGE W. BEAR.
